UNITED STATES PATENT OFFICE.

WARREN MACPHERSON, OF CAMBRIDGE, AND ERNEST W. DUNBAR, OF HUDSON, MASSACHUSETTS, ASSIGNEES TO CAMBRIDGE RUBBER COMPANY, OF CAMBRIDGE, MASSACHUSETTS, A CORPORATION OF MASSACHUSETTS.

OVERSHOE AND PROCESS OF MANUFACTURING THE SAME.

Application filed April 28, 1924. Serial No. 709,363.

To all whom it may concern:

Be it known that we, WARREN MACPHERSON and ERNEST W. DUNBAR, citizens of the United States, residing, respectively, at Cambridge, Middlesex County, State of Massachusetts, and Hudson, in said county and State, have invented a new and useful Improvement in Overshoes and Processes of Manufacturing the Same, of which the following is a specification, like reference characters on the drawings indicating like parts in the several figures.

This invention relates to overshoes of the arctic type. Such overshoes include a rubber bottom and a cloth top with fastenings, usually buckles, for securing the opposite edges of the upper around the ankle of the wearer. The cloth upper usually includes an outer fabric and a lining united thereto by an intermediate coating of rubber, and the buckles are secured to straps which are anchored between the lining and the outer fabric, both ends of each strap being secured between these fabric pieces so that the straps form loops which project beyond the edge of the upper. Due to the presence of these loops, it has always been considered impractical to bind the edges of the upper, and consequently they have been left "raw" or unbound both at the top and also at the front of the shoe. While the rubber coating does reduce the tendency of the fabric to fray, it does not prevent it, especially with woven fabrics. It is the chief object of the present invention, therefore, to improve the construction of overshoes of the type mentioned with a view to effectually preventing the fraying of the exposed edges of the upper. The invention also aims to devise a process of manufacturing overshoes which will attain the end just mentioned without adding materially to the expense of manufacture of the shoe.

The nature of the invention will be readily understood from the following description when read in connection with the accompanying drawings, and the novel features will be particularly pointed out in the appended claims.

Referring now to the drawings,

Figure 1 is a perspective view of an overshoe embodying the invention in the form at present preferred;

Fig. 2 is a cross sectional view through the top of the overshoe just below the upper edge thereof;

Fig. 3 is a cross sectional view on a large scale through one of the buckle supporting straps and the parts of the top immediately associated therewith;

Fig. 4 is a cross sectional view on a large scale through the edge binding of the upper; and

Fig. 5 is a front elevation of parts of the upper immediately adjacent to the bound edge, these parts being shown somewhat magnified.

The shoe shown comprises a rubber bottom 2 and a cloth top 3, this shoe being substantially like the present construction except for the features of difference herein-after pointed out. In the particular shoe shown the top or upper includes two side pieces 4 and 5, Fig. 2, which are united at the back of the shoe by a seam 6. The parts 4 and 5 form the outer fabric of the upper, and they are secured to inner lining pieces 7, 8 and 9 by means of an intermediate coating of rubber. The side pieces 4 and 5 are also adhesively united to a fabric piece 10 which forms part of the bellows tongue, this piece usually being integral with the vamp of the shoe. A portion of the member 10 is also secured to the lining pieces 7 and 8. The construction so far described is not materially different from that of the ordinary overshoe.

According to the present process the front and top edges of the outer or side pieces 4 and 5 are bound, preferably by overseaming, as indicated at 12. This overseaming is done after the side pieces have been cut out and before they are secured to the lining, and this operation can be performed very rapidly with the aid of a suitable sewing machine such, for example, as that known commercially as the "Merrow binder." When the binding operation has been completed, the lining pieces 7, 8 and 9 are secured to the side pieces, the upper edges of the lining pieces being located slightly inside or below the bound edges of the parts 4 and 5, as clearly shown in Fig. 1. The edges of the lining pieces may overlap the binding stitches slightly, but preferably they come just to the stitches.

The clasps and cooperating eye pieces of the buckles preferably are secured to the opposite edges of the upper by rubber straps or stays 14, each strap being doubled upon itself, as clearly shown in Fig. 3, to form a loop. Four of these straps are adhesively anchored between the two plies 4 and 10, at one edge of the upper, and four more between the plies 5 and 10 at the opposite side of the shoe. Both the inner and outer fabrics 4 and 10 have their inner surfaces coated with rubber, and in securing them together the straps or stays 14 are located properly on the inner surface of the part 4, and the piece 10 is then placed on the part 4 and the two parts are pressed together to cause their tacky surfaces to adhere, the edge of the inner fabric 10 preferably being located just within the bound edge of the outer fabric 4, as clearly shown in the drawings. This operation secures the stays or loops 14 firmly between the inner and outer plies of the upper. The same process is followed in anchoring the straps between the parts 5 and 10 at the opposite side of the shoe and in securing these parts together.

The remaining manufacturing operations may be carried out in any suitable manner. These operations usually include the assembling of the parts of the shoe in the proper relationship to each other on a last, the varnishing of the rubber bottom, and the vulcanizing of the shoe.

The completed shoe is shown in Fig. 1, and it will be observed that it presents a much neater appearance than shoes of this type made in the usual manner. The exposed edges of the parts 4 and 5 of the upper are effectually prevented from fraying by the binding stitches 12, and the location of the edges of the parts 7, 8, 9 and 10 just within the bound edges, enables this binding also to protect the edges of the latter pieces. As above stated, the binding operation can be performed very rapidly so that the present process involves an increase in the expense of manufacture of the shoe which is negligible when compared with the advantage produced. This arrangement materially improves the shoe since it gives the shoe the appearance of having a bound edge both inside and outside. Furthermore, it has the very important advantage of permitting the manufacture of the cloth top from a woven fabric. Heretofore it has been the universal practice to make the cloth top of knitted fabric, but this invention enables us to use a woven fabric successfully and thus to reduce substantially the manufacturing cost of the shoe. At the same time, the invention is of material value in a shoe having a knitted fabric top.

Having thus described our invention, what we desire to claim as new is:

1. An overshoe of the arctic type comprising a rubber bottom and a cloth upper, said upper including outer and inner plies of fabric secured together, fastening means secured between said plies at one of the front edges of said upper to facilitate the fastening of the shoe about the ankle of the wearer, and a binder protecting the edge of one of said plies, the edge of the other ply being located slightly inside of the bound edge of the first ply. 75

2. An overshoe of the arctic type comprising a rubber bottom and a cloth upper, said upper including outer and inner plies of fabric, the edge of said outer ply being overseamed and the inner ply being adhesively united to said outer ply with its edge lying just inside the bound edge of said outer ply, straps anchored between said plies at the opposite edges of said upper at the front of the shoe, and cooperating fastening devices secured to said straps and adapted to fasten the upper of the shoe about the ankle of the wearer. 80

3. An overshoe of the arctic type comprising a rubber bottom and a cloth upper folded to form a bellows top, said upper including quarters and a bellows tongue, the edges of said quarters which extend up the front of the shoe being overseamed and the opposite edges of said bellows tongue being overlapped upon and united by means other than the overseam to the overseamed margins of said quarters, and cooperating fastening devices secured between the edge portions of said tongue and quarters to facilitate the fastening of the shoe about the ankle of the wearer. 90

4. That improvement in the process of manufacturing arctic overshoes having cooperating fastening for securing the opposite edges of the upper together along the front of the ankle, which consists in cutting the parts of the upper out of suitable fabric, overseaming the edges of the quarters, securing fabric pieces to the inner surfaces of said quarters with the edges of said inner pieces located slightly inside said overseamed edges, inserting fastener supporting straps between the edge portions of said quarters and inner pieces before they are united to anchor said straps securely between said parts, and then completing the manufacture of the overshoe in any suitable manner. 105

In testimony whereof we have signed our names to this specification. 120

WARREN MACPHERSON,
ERNEST W. DUNBAR.
